UNITED STATES PATENT OFFICE.

GAETANO CORBELLA AND GUALTIERO LONGONI, OF MILAN, ITALY.

VALVE-CONTROLLING MECHANISM.

1,414,624.

Specification of Letters Patent. Patented May 2, 1922.

Application filed December 24, 1917. Serial No. 209,428.

(GRANTED UNDER THE PROVISIONS OF THE ACT OF MARCH 3, 1921, 41 STAT. L., 1313.)

To all whom it may concern:

Be it known that we, GAETANO CORBELLA and GUALTIERO LONGONI, subjects of the King of Italy, residents of Milan, in the 5 Kingdom of Italy, No. 3 Via Lavanderie Sociali, Milan, have invented new and useful Improvements in Valve-Controlling Mechanism, (for which we have filed application in Italy Nov. 18, 1916, patent granted Nov. 10 30, 1916, No. 156,920, Gen. Reg.,) of which the following is a specification.

The object of the present invention is an improvement in the mechanism for operating valves, especially for internal combustion engines, greater lightness and simplicity being obtained than with the mechanisms used heretofore.

The annexed drawings show one method of carrying the invention into effect by way 20 of example.

Fig. 1 shows in section the cylinder head of an internal combustion engine fitted with valve controlling mechanisms according to the present invention.

Fig. 2 shows a detail of the operating mechanism of coaxial valves.

Figs. 3 and 4 show a modified valve operating mechanism in side view and plan respectively.

—*a*— and —*b*— are coaxial valves. The inner one —*a*— has for its seat the inner periphery of the outer valve —*b*—; —*g*— is the spindle of —*a*— and —*h*— is the hollow spindle of —*b*—; both spindles are 35 operated against the action of the respective springs —*c*— and —*d*— bearing against discs —*e*— and —*f*— respectively.

As indicated in the drawing, both valves are operated by one and the same cam actuating a rod —*i*— hinged to one end of the double arm lever —*l*—. The opposite end of the lever —*l*— is fork-shaped and the two fork-shanks —*m*— actuate the disc —*f*— of the valve —*b*— directly, whilst the spindle —*g*— of the valve —*a*— is actuated by the lever —*l*— indirectly through the bolt —*n*— and double arm lever —*p*—, the bolt —*n*— being vertically slidable in the guiding support —*q*— rigidly secured to the 50 cylinder end, and the lever —*p*— being pivotally mounted on a fixed bracket likewise rigidly secured to the cylinder end and facing the top end of the spindle —*g*—.

Consequent on this arrangement the

valves —*a*— and —*b*— are actuated alternately, that is to say, when the end —*m*— of the lever —*l*— presses down and opens the valve —*b*—, it does not operate the spindle —*g*— of the valve —*a*—, which consequently remains closed, whereas when the end —*m*— of the lever —*l*— is raised and releases the disc —*f*— thus leaving the valve —*b*— closed, the bolt —*n*— causes the lever —*p*— to swing on its pivot and its outer end to depress the spindle —*g*—, thus 65 opening the valve —*a*—.

A modified construction is shown in Figs. 3 and 4, wherein the lever —*l'*— fitted with end fork —*m'—m'*—, instead of acting by pushing a bolt, forms one side of a hinged 70 parallelogram, comprising a link —*j*— one end of which is pivotally connected to said lever —*l'*—. The other end of link —*j*— is pivoted at —*r*— to one —*s*— of a pair of levers —*s*— and —*s'*— respectively fulcrumed at —*t*— and —*t'*— in a suitable support (not shown), which may be a bracket such as that in which lever —*l*— is pivotally supported in the embodiment shown in Fig. 1. The levers —*s*— and —*s'*— are pivotally connected with one another as by a pin and slot connection shown at —*u*—, the outer end —*v'*— of the lever —*s'*— being adapted to act upon the spindle —*g*—. As may be readily seen, the ends 85 —*v'*— and —*m'*— of the opposite sides —*l'*— and —*s—s'*— of the articulated parallelogram will move in opposite directions upon actuation of the pivoted end of lever —*l'*—. In other words by depressing the 90 pivoted end of lever —*l'*— the parts —*v'*— and —*m'*— will be moved towards each other as shown in dotted lines in Fig. 3, and by raising the pivoted end of lever —*l'*— the said parts will be moved away from 95 each other. As in the embodiment illustrated in Figs. 1 and 2 the arrangement is such that the valve operating levers may be actuated by a single controlling member such as the rod —*i*—.

Having now described our invention and how the same is to be carried out, what we claim as our invention, is:

1. In a valve controlling mechanism, the combination with two valves, of a stationary support and means for alternately operating said valves, said means comprising two valve controlling levers pivoted in said sup-

port, an actuating member adapted to move in opposite directions and so operate one of said levers, and a member interposed between said levers and movable relatively 5 thereto for transmitting the movements of the last mentioned lever to the other lever and reversing the direction of said movements.

2. In a valve controlling mechanism, the 10 combination with two valves, of a stationary support and means for operating said valves, said means comprising two valve controlling levers pivoted in said support, an actuating member adapted to move in opposite directions and so operate one of said levers, and 15 a member intermediate the two levers having a sliding engagement with said support.

3. In a valve controlling mechanism, the combination with two valves, of a stationary support and means for operating said valves, 20 said means comprising two valve controlling levers pivoted in said support, an actuating member adapted to move in opposite directions and so operate one of said levers, and a bolt engaging said levers on opposite sides 25 of their respective pivots, said bolt being slidably mounted in said support.

In testimony whereof we affix our signatures.

G. CORBELLA.
GUALTIERO LONGONI.
